LUG STRAP HOLDER

Heyward Shealy, Hendersonville, N. C.

Application July 28, 1936, Serial No. 93,084

2 Claims. (Cl. 139—154)

This invention relates to improvements in looms, more especially in holders for the lug straps of the picker sticks therein, and its objects are as follows:

5 First, to provide a lug strap holder for loom picker sticks which enables the lug strap to work more freely than do other known holders, eliminates the need for making screw or other holes in the picker stick for its attachment and, consequently, prevents the picker stick from splitting because of avoiding weakening it.

10 Second, to apply the clamp casting to the picker stick below the lug strap so that the top of the casting, which is arched for the purpose, can afford an enduring support and bearing 15 for the lug strap.

Third, to provide said clamp casting with at least one hole into which a portion of the retainer and buffer strap bulges when the U-clip 20 is drawn up tightly, thereby to form a key which aids in keeping said strap from slipping.

Fourth, to make the clamp in the form of a forked casting which, because of this form, is fitted against three sides of the picker stick, the 25 U-clip and its saddle covering the fourth side, all below the center of gravity of the stick, the arrangement thus made giving the picker stick such balance that the stick can be driven to perform its pick with a minimum of power.

30 Other objects and advantages will appear in the following specification, reference being had to the accompanying drawing, in which:

Figure 1 is a side elevation of a picker stick showing the improved lug strap holder applied.

35 Figure 2 is a perspective view of said holder, a portion of the picker stick being shown.

Figure 3 is a partially sectional and elevational view, especially illustrating how a portion of the retainer of buffer strap bulges into the hole 40 in the clamp casting.

It is common knowledge that picker sticks by which the shuttles are thrown back and forth along the race plate in a loom, will break upon occasion because of the heavy duty that they 45 are required to perform. This breaking or splitting is due, in a large measure, to the fact that the picker sticks are weakened by the screw or other holes which are made necessary by the prevailing types of lug strap holders. One of the 50 purposes of the invention is to avoid the necessity of making any hole in the picker stick for the purpose of attaching the lug strap holder. One of the main causes of the picker stick breaking or splitting, is thereby eliminated.

55 In the drawing, 1 designates a picker stick

of any known type. This is generally made of straight-grained hard wood. The only hole that it has is designated 2, and this is for the purpose of attaching the strap (not shown) of a parallel-motion device with which the invention has 5 no concern.

The lug strap 3 is of any known kind, and it goes around the picker stick in the form of a loop, the matching holes 4 in its free ends constituting the place of connection of what is 10 known as a lug stick (not shown) that extends inwardly of the loom and is ultimately actuated by the cam of the picking motion or some equivalent thereof.

The invention comprises a holder generally 15 designated 5. This consists of a clamp casting 6 which is forked at 7 so as to provide two arms 8. These fit against the sides of the picker stick 1 when the latter occupies the fork, the face portion 9 of the casting 6 then lying adjacent to the 20 front face of the picker stick. The arms 8 are connected with the face portion 9 by braces 10. The metal comprising the arms 8 and braces 10 could be made solid, but it is more desirable to have the hollow places shown, and to thus define 25 the braces because this arrangement avoids making the casting objectionably heavy and does not sacrifice any mechanical strength.

While on the point of mentioning the weight of the casting, one of the purposes of the invention is to apply the casting to the picker stick below the center of gravity of the stick. The forks and face portion of the casting 6 hug three 30 sides of the stick as closely as possible, the U-clip saddle hugging the fourth side. This brings 35 all of the metal very close to the picker stick so that the latter is given a fine balance which enables it to be worked very efficiently.

The previously mentioned saddle now designated 11, has a crotch in which the U-portion 40 of a clip 12 is seated. The ends of the latter go through appropriately placed holes in the casting 6, coming out in front of the face portion 9 where nuts 13 are screwed on to the threads. When the latter are driven home tightly they 45 cause the casting to press against that part of the retainer or buffer strap 14 that is interposed between the face portion 9 and the front face of the picker stick 1. The face portion has a fairly large hole 15 and when pressure is applied, 50 a portion 16 (Fig. 3) of the retainer strap bulges into the hole, thereby forming a key which aids in keeping said strap from slipping.

The remaining portion of the strap 14 that extends above the holder 5 is provided with a T- 55

head 17. The lug strap 3 is fitted between the T-head and the two arms 8 and it is here that the lug strap is held.

It will be noticed that the top of the casting 6, 5 more specifically the tops on the arms 8, is arched at 18. This arch provides a better bearing for the lug strap 3 than if the casting were made otherwise. The lug strap is attached loosely to the picker stick and at times it will ride upon the 10 casting 6, being substantially confined to its bearing at 18 by the T-head 17. It is for this purpose that the casting is clamped on to the picker stick below the lug strap. The casting therefore provides an enduring support for the lug strap.

15 By virtue of the fact that the picker stick does not need any holes for the attachment of the improved holder 5, splitting from this particular source of weakening is eliminated. The application of the clamp casting 6 below the center of 20 the gravity of the picker stick and below the lug strap 3 respectively improves the balance of the picker stick and provides a good bearing for the lug strap. The provision of the hole 15, although of utmost simplicity, insures the unfailing retention of the buffer strap 14 because of the bulge 25 16 that is raised when pressure is applied.

I claim:

1. In a picker stick, a lug strap holder compris-

ing a clamp which consists of a face portion that comes adjacent to the front face of the picker stick and has arms that fit against two sides of the picker stick, said clamp including a saddle 5 that fits against the fourth side of the picker stick and has a U-clip extending from the saddle through the face portion where it carries securing nuts, a buffer strap of which a part is interposed between the said face portion of the clamp and the front face of the picker stick, the remaining 10 part of the buffer strap having a T-head, and means by which to hold the buffer strap from slipping in addition to the pressure exerted thereagainst by the face portion when said nuts are tightened.

2. In a picker stick, a lug strap holder comprising a forked clamp which is fitted upon the picker stick, said clamp having a hole in its face portion, a buffer strap of which a part is interposed between the face portion of the clamp and the adjacent face of the picker stick, and means going around the picker stick and through the clamp, drawing the clamp tightly against the buffer strap so that a portion of said strap is made to bulge 20 into the hole thereby forming a key which aids in 25 keeping said strap from slipping.

HEYWARD SHEALY.
